UNITED STATES PATENT OFFICE.

JOHAHN DIESCHBURG, OF ECHTERNACH, GERMANY, ASSIGNOR TO J. P. WEBER, OF PHOENIXVILLE, PENNSYLVANIA.

KNEADING-MACHINE.

SPECIFICATION forming part of Letters Patent No. 793,283, dated June 27, 1905.

Application filed December 7, 1903. Serial No. 184,130.

To all whom it may concern:

Be it known that I, JOHAHN DIESCHBURG, a subject of the Emperor of Germany, residing at Echternach, in the Grand Duchy of Luxembourg, Germany, have invented a new and useful Improvement in Kneading-Machines, of which the following is a specification.

My invention relates to a machine for kneading dough; and the object of the invention is 10 to produce a machine of this character which will facilitate bread and cake making.

My invention consists in the novel features of construction and combination of parts hereinafter described, particularly pointed out in 15 the claims, and shown in the accompanying drawings.

Figure 1 is a perspective view of my machine. Fig. 2 is a longitudinal section through the machine, parts being shown in elevation. 20 Fig. 3 is a detail view, partly in elevation, showing the guide-pin lifted from the spiral groove. Fig. 4 is a detail view, partly in section and at right angles to the view in Fig. 3, showing the pin in engagement with the 25 groove. Fig. 5 is a plan view showing in detail the construction of parts located at the right-hand end of the frame shown in Fig. 1. Fig. 6 is a detail sectional view of the gear-wheel which meshes with the worm-gear shown 30 in Fig. 5. Fig. 7 is a detail view, partly in section, showing the kneading-arms.

In constructing my device I employ a table A, having suitable side and end pieces and having central transverse cross-pieces A'. The 35 cross-pieces A' extend downward below the plane of the table, which is cut out between them. Suitable side and bottom pieces are arranged in connection with the pieces A', whereby is formed a central kneading-recep- 40 tacle B, supported by the table A.

Extending below the bottom of the table proper, but passing transverse through the receptacle B, is a shaft B', longitudinally grooved adjacent one end and having a double 45 spiral groove B² formed adjacent the opposite end. On the shaft in the receptacle are arranged side by side two collars C C', each carrying oppositely-disposed arms, one arm of each collar being straight and the other

forming a compound curve. The arms C² of 50 the collar C are solid, while the arms C³ of the collar C' are bifurcated or slotted, as is clearly shown in Fig. 2.

To drive the shaft B' and the arms C² and C³, a shaft D is journaled in the table adjacent and at right angles to the longitudinally-slotted portion of the shaft B', and a hand-wheel D' is secured to the outer projecting end of this shaft. On this shaft, arranged within a suitable casing D², is a worm-gear 60 D³. This worm-gear meshes with a gear-wheel B³, splined on the shaft B'.

The operation of the machine will be obvious. Dough to be kneaded is placed in the receptacle B and is worked and mixed by means of 65 the rotation of the arms C² and C³. To further effect a thorough kneading of the dough by giving a longitudinal movement to the shaft B' simultaneous with its rotation, I arrange a pin E in a bracket F, which pin is enlarged and curved at its lower end to fit in the spiral groove B². The pin has two annular grooves E' formed on its upper portion. The shaft B' is journaled in the lower portion 70 of the bracket F, and a spring is secured at its lower end to the bracket, as at H, and the upper end of this spring is adapted to engage one of the grooves E', the upper portion of the spring H being bent and extended through an aperture formed in the upper part of the 75 bracket. When the upper end of the spring is in engagement with the upper groove E', the lower end of the pin will be held in engagement with the groove B² and a longitudinal movement will be imparted to the shaft, 80 which movement is permitted by the longitudinal groove in the opposite end of the shaft in which the spline of the gear-wheel B³ loosely rests. By lifting the pin so that the upper 85 end of the pin will engage the lower groove 90 on the pin the latter will be held out of engagement with the groove, and the shaft can be quickly and freely adjusted by sliding it to the desired position. The shallow trays arranged on each side of the receptacle B can 95 be used for any desired purpose—for holding flour or an additional supply of dough, for example. It will be further noted that the

collars C and C' are slideable on the shaft B' and are secured in their adjusted position by means of the cotter-pins C^t, carried by each collar. This construction permits the spacing apart of the collars.

Having thus fully described my invention, what I claim as new, and desire to secure by Letters Patent, is—

1. The combination with a receptacle, a rotatable shaft passing therethrough, a double spiral groove on said shaft exterior of the receptacle, a stationary pin adapted to engage said groove, and arms carried by the shaft and adapted to rotate within the receptacle, substantially as described.

2. A device of the kind described comprising a receptacle, a shaft passing therethrough,

said shaft having a spiral groove adjacent one end and a longitudinal groove adjacent the opposite end, a pin adapted to engage the spiral groove, means for holding the pin out of engagement with the groove, a gear - wheel loosely splined on the longitudinally-grooved portion of the shaft, a shaft arranged transverse to the grooved shaft, and a worm-gear arranged on the said transverse shaft and adapted to mesh with the gear-wheel carried on the grooved shaft, as and for the purpose described.

J. DIESCHBURG.
